UNITED STATES PATENT OFFICE.

ROYAL MATTICE, OF PHILADELPHIA, PENNSYLVANIA.

WELDER'S TONGS

Application filed July 7, 1921. Serial No. 432,818.

To all whom it may concern:

Be it known that I, ROYAL MATTICE, a citizen of the United States, residing at Philadelphia, in the county of Philadelphia and State of Pennsylvania, have invented certain new and useful Improvements in Welders' Tongs, of which the following is a specification.

The present invention has to do with certain improvements in welders' tongs which are used for conducting and delivering the electrical current to the electrode used in an electric welding operation. These tongs are provided with jaws by means of which the electrode is gripped. In the past it has been the almost universal custom to attach the electric cables directly to such jaws and at a point in advance of the handle grip. These electric cables are generally flexible, but owing to the magnitude of the current used, it is necessary to use such a large cable that it can be conveniently attached directly to the jaws; but when so attached it is liable to become broken owing to the constant bending, besides which it seriously interferes with the convenient manipulation of the tongs during the welding operation.

One of the objects of the present invention is to provide a construction in which the electric cable may be attached to the tong at a point back of the handle grip, the current being then conducted past or through the handle grip to the jaws themselves. When this arrangement and form of tongs is provided it may be very easily and conveniently manipulated, so that the quality of the work may be much improved.

Owing to the magnitude of the electric current which is used during the welding operation, it is necessary to employ a relatively large conductor for carrying the current through or past the handle grip as otherwise such conductor would become overheated. In fact even when using a conductor of relatively large size a considerable amount of heat is generated. Furthermore, it is very desirable to insulate the conductor in that portion adjacent to the handle grip itself, so as to protect the operator from electric shock. In some cases I form the handle grip itself of heat insulating material so that it serves the double function of protecting the operator against shock, and also against burning by heat.

Another feature of the invention in this

connection has to do with the provision of handle grips of such form that they will very readily dissipate the heat generated by the flow of current through the conducting portion. For this purpose, I sometimes provide the insulating material of the handle grip with slots or openings allowing the free circulation of air directly to the electrical conductor itself.

Other objects and uses of the invention will appear from a detailed description of the same, which consists in the features of construction and combinations of parts hereinafter described and claimed.

In the drawings:

Figure 1 shows a longitudinal section through a pair of tongs embodying the features of the present invention, said tongs including a pair of pivoted members which provide jaws for clamping the electrode;

Fig. 2 shows a cross section taken on the line 2-2 of Fig. 1, looking in the direction of the arrows;

Fig. 3 shows a longitudinal section through another form of tongs provided with a single handle member carrying a pair of jaws which may be drawn together by means of a suitable clamping device;

Fig. 4 shows a fragmentary face view of the clamping device of one of the jaws of the tongs of Fig. 3, being taken on the line 4-4 of Fig. 3 looking in the direction of the arrows;

Fig. 5 shows a cross section taken on the line 5-5 of Fig. 3, looking in the direction of the arrows; and

Fig. 6 shows a cross section taken on the line 6-6 of Fig. 3, looking in the direction of the arrows.

Referring first to the arrangement shown in Figs. 1 and 2, the same includes a pair of members 7 and 8. These members include the conducting elements 9 and 10 which are of relatively large cross section as shown in Fig. 2, sufficient in fact to carry the large currents necessary without material overheating.

The conducting elements 9 and 10 are pivoted together at the point 11 and their end portions provide the co-operating jaws 12 and 13. The inner face of the jaw 13 is provided with a lining 14 held in place by means of the screws 15, said lining being of conducting metal, but replaceable so that it may be renewed from time to time in case of damage by burning.

The lower ends of the conducting members 9 and 10 terminate in the conducting lugs 16 and 17 respectively to which may be attached the terminals 18 and 19 by means of wing nuts or the like 20 and 21.

The current from the connectors 18 and 19 flows directly through the elements 9 and 10 to the jaws. These elements 9 and 10 are protected by means of heat and electrically insulating covers 22 and 23 which constitute the handle grips. In order to facilitate the ventilation of the conducting elements 9 and 10, I prefer to form them with irregular surfaces as shown in Fig. 2, so as to establish the air passages 24 which materially facilitate the ventilation and consequent cooling of the conducting elements. It will also be observed from Fig. 2 that each of the conducting elements illustrated is of a channel-shaped cross section and that a spring member 25 has its end portions 26 and 27 seated in the channels of the members 9 and 10, tending to force said members apart and thus bring the jaws together. The inner surfaces of the conducting members 9 and 10 are also exposed to the cooling influence of the freely circulating air.

In the construction shown in Figs. 3, 4, 5, and 6, there is but one single relatively large conducting element 28, to the lower end 29 of which may be removably attached a connector 30 by means of the bolt 31. The conducting element 28 at its inner end carries the jaws 32 and 33 which are secured to it by means of a through bolt 34, the jaws normally tending to separate from each other by reason of their spring quality. A wing nut 35 is provided on the cross bolt 36 for forcing together the end portions 37 and 38 of the jaws. These end portions may be provided with the channels or serrations 39 as illustrated in Fig. 4.

The handle portion of this construction includes the semi-circular heat and electrically insulating members 40 and 41, drawn together in their central portions by means of a cross bolt 42. These insulating members 40 and 41 are preferably formed on a smaller curvature than the curvature of the conducting element 28, so as to establish the air passages 43 and 44 which extend longitudinally through the tongs and serve to effectively ventilate the adjacent portions of the element 28. I also prefer to cause the

members 40 and 41 to stop short of each other as shown particularly in Figs. 5 and 6, so as to establish the additional air passages 45 and 46 therein illustrated.

While I have shown and described only certain embodiments of my present invention, still it will be observed that in each case the electrically conducting member constitutes a portion of the handle of the device; that the electric cable is adapted to be attached to said conducting member beyond said handle portion, so that the current flows through the handle portion; that the handle portion itself is provided with heat and electrically insulating grips; and that the entire arrangement is so formed that the electrically conducting member is effectively ventilated and thereby cooled.

I claim:

A device for gripping and holding electrodes for electric welding comprising a pair of companion members each of which consists of an elongated metallic bar of electrically conducting material having at one end a flattened connector element adapted to receive a flattened cable terminal, and having at its other end a flattened jaw for electrical contact with an electrode member, all of said parts for each of said contacting members being integrally formed from its terminal connector to its jaw, whereby electric current may flow through said member from the terminal connector to the jaw with a minimum of resistance and consequent heating, the contacting members being provided with co-operating projections on their adjacent faces adjacent to their jaws, a pivotal connection between the projections of the two members, the two members being angularly formed with respect to each other whereby when their jaws are in flat contact their body portions are separated at the other side of said pivotal connection, a U-shaped spring between said body portions tending to separate them to thereby force the jaws towards each other, and a handle grip of heat and electrically insulating material mounted on each of said body portions, there being passages for the free circulation of air between each body portion and the handle grip thereon, substantially as described.

ROYAL MATTICE.
